(57) **CLAIM**

The new design for a housing for a condenser, as shown and
described herein.

DESCRIPTION

FIG. 1 is perspective view of a housing for a condenser of
the present invention;

FIG. 2 is a front elevation view of the housing for a
condenser of the present invention;

FIG. 3 is a first side elevation view of the housing for a
condenser of the present invention;

FIG. 4 is a second side elevation view of the housing for a
condenser of the present invention;

FIG. 5 is a rear elevation view of the housing for a condenser
of the present invention;

FIG. 6 is a top plan view of the housing for a condenser of
the present invention; and,

FIG. 7 is a bottom plan view of the housing for a condenser
of the present invention.

1 Claim, 5 Drawing Sheets
